J. A. ROBERTSON,
FILM DEVELOPING APPARATUS,
APPLICATION FILED MAY 5, 1917.

1,275,753.

Patented Aug. 13, 1918.

UNITED STATES PATENT OFFICE.

JOHN A. ROBERTSON, OF ROCHESTER, NEW YORK, ASSIGNOR TO EASTMAN KODAK COMPANY, OF ROCHESTER, NEW YORK, A CORPORATION OF NEW YORK.

FILM-DEVELOPING APPARATUS.

1,275,753.

Specification of Letters Patent. Patented Aug. 13, 1918.

Application filed May 5, 1917. Serial No. 168,557.

To all whom it may concern:

Be it known that I, JOHN A. ROBERTSON, of Rochester, in the county of Monroe and State of New York, have invented certain new and useful Improvements in Film-Developing Apparatus; and I do hereby declare the following to be a full, clear, and exact description of the same, reference being had to the accompanying drawings, forming a part of this specification, and to the reference-numerals marked thereon.

My present invention relates to photography and more particularly to photographic developing apparatus and it has for its object to provide a device of a compact and simple nature adapted for the daylight development of photographic roll film. Further objects of the invention are to provide a device that may be produced at low cost and used by amateurs of slight experience and improvements are directed toward the manner in which the film is unrolled or extended and held extended in contact with the developing solution. To these and other ends the invention resides in certain improvements and combinations of parts all as will be hereinafter more fully described, the novel features being pointed out in the claims at the end of the specification.

30 In the drawings:

Figure 1 is a top plan view of a developing apparatus constructed in accordance with and illustrating one embodiment of my invention;

35 Fig. 2 is a longitudinal section therethrough taken on the line 2-2 of Fig. 1 but showing the parts in a different position;

40 Fig. 3 is a similar section showing still another position;

Fig. 4 is an enlarged plan view of the roll holding end of the tank;

Fig. 5 is an enlarged bottom plan view of the film attaching end of the cover, and

45 Fig. 6 is a cross section taken substantially on the line 6-6 of Fig. 1.

Similar reference numerals throughout the several views indicate the same parts.

The present device is particularly adapted for the development of the smaller sizes of film cartridges and it embodies a preferably rectangular elongated tank 1 of sufficient length to accommodate the film strip in an extended and flat condition. At the

upper edges of the side walls of the tank 55 are laterally turned side flanges 2 that are cut away at 3 near one end. At this same end is provided a spool or roll holder embodying a transverse bar 4 supported by the side walls of the tank and spaced from the bottom thereof. The tank is provided with a sliding cover 5 having inturned edge flanges 6 on its side adapted to engage beneath and run on the flanges 2 of the tank in a light tight manner. The flanges 6 are 60 cutaway at 7 at the forward or advance end of the cover so that the latter and the tank in the region of the cutaway portions 3 of the tank may be overlapped before their respective flanges are engaged or interlocked 70 with each other.

The said advance end of the cover is also provided with a combination light guard and film guide 8 in the form of a depending flange coextensive with the interior cross 75 sectional area of the tank. The bottom of the flange is preferably curled rearwardly as at 9 while bracket webs 10 at the sides serve to strengthen it. Just back of the flange on top of the cover is an offset bridge 80 plate 11 preferably provided with impaling teeth 12 at its rear edge. When the cover is slid to its closed position as in Fig. 1, it engages beneath spring side clips 13 on an overhanging flange 14 at that end of the 85 tank, which flange has a cutaway portion 15 to receive the bridge plate 11.

The mode of operation is as follows:

A film spool 16 carrying an exposed film roll 17 is dropped into the end of the tank 90 1 between the bar 4 and the end wall of the tank where it is confined for rotation with the flanges of the spool riding against the bar, as shown in Fig. 2. The film roll is composed of the sensitive inner strip 18 and 95 the paper or other outer backing strip 19 and the extremity 20 of the backing strip is unwound and passed under the guard flange 8, thence over the end of the cover 5 beneath the bridge plate 11 and impaled upon 100 the teeth 12 of the latter. This is done while the cover and tank are held as in Fig. 2 with their respective flanges 6 and 2 about to be engaged or just engaged, the guard 8 being admitted to the interior of the tank 105 ahead of the bar 4 and the film roll 17. The tank is now filled with developer (indicated at 21 in Fig. 3) and the

cover shoved longitudinally of the tank into closed position as in Fig. 1. This operation unrolls the film and disposes it as shown in Fig. 3 along the bottom of the tank with the sensitive strip 18 uppermost. The tray may then be rocked or otherwise manipulated as customary with such devices to perfect the development. When development has been completed, the cover is opened again or partially opened and the film strip pulled out, completely unwinding it from the spool 16.

It will be noted that when extended the film is disposed with the sensitive surface uppermost so that bubbles are less likely to adhere thereto without being dislodged, the body of the developer lying above the film. The whole device may be made out of sheet metal at a low cost and is both light and so constituted as to comprise only two parts.

I claim as my invention:

1. In a film developing apparatus, the combination with a tank having a roll holder at one end, of a sliding cover co-operating with the tank in a light tight manner to move from end to end thereof, and a fixed film attaching means at the advance end of the cover.

2. In a film developing apparatus, the combination with a tank having a roll holder at one end, of a sliding cover for the tank and a depending light guard and film guide at the advance end of the cover.

3. In a film developing apparatus, the combination with a tank having a roll holder at one end, of a sliding cover for the tank, a depending light guard and film guide at the advance end of the cover, and

a film securing device on the cover above 40 the guard.

4. In a film developing apparatus, the combination with a tank having a sliding cover and adapted to accommodate a film strip in a flat and extended position, of a 45 roll holder at one end of the tank embodying a raised transverse bar between which and the end of the tank a film roll is adapted to be confined for rotation.

5. In a film developing apparatus, the 50 combination with a tank having a roll holder at one end and a sliding cover, of a film securing device at the advance end of the cover comprising a transverse bridge piece spaced from the cover and around 55 which the extremity of the film is adapted to be looped.

6. In a film developing apparatus, the combination with a tank having a roll holder at one end and a sliding cover for 60 the tank, of a depending light guard and film guide on the advance end of the cover comprising a flange coextensive with the interior cross section of the tank and having 65 a curved lower edge traveling close to the bottom of the tank as the cover is applied.

7. In a film developing apparatus, the combination with an elongated tank, of a 70 cover for the latter having a sliding engagement therewith longitudinally of the tank and means for unrolling a film roll contained in the tank through the relative movement of the cover and tank.

JOHN A. ROBERTSON.
